UNITED STATES PATENT OFFICE.

WALTER CHIPPERFIELD, OF HORNCURCH, ENGLAND, ASSIGNOR TO RONEO LIMITED,
OF LONDON, ENGLAND, A COMPANY OF GREAT BRITAIN.

METAL FILING-CABINET.

1,353,452.

Specification of Letters Patent. Patented Sept. 21, 1920.

Application filed November 13, 1919. Serial No. 337,831.

To all whom it may concern:

Be it known that I, WALTER CHIPPERFIELD, a subject of the King of Great Britain, residing at "Kinkora," Great Nelmes, 5 Hornchurch, in the county of Essex, England, have invented new and useful Improvements in Metal Filing-Cabinets and in the Construction of Sliding Drawers Therefor, of which the following is a specification.

10 The present invention relates to improvements in the construction of metal cases for containing shelves, drawers and the like, and further relates to the construction of sliding or other drawers or receptacles to 15 be contained therein.

In such metal structures some difficulties are experienced in the packing and transport of same from place to place, and it would therefore be of considerable advantage to provide a satisfactory construction 20 by which the parts composing the structure could be disassembled into convenient sections for package and transport, and then the parts readily assembled and connected together; but to carry this out successfully 25 certain essential conditions have to be provided for, as for instance the assembling of the parts of the structure so that it will comprise a rigid whole, which must be capable 30 of being effected with little if any mechanical skill, so that it must not be necessary in so assembling to bend any parts, or to employ screws, bolts or pins, and having been 35 so erected the structure must be rigid and substantial.

The present invention provides constructions by which the above requirements can be efficiently carried out.

A primary feature of this invention consists in means, as hereafter described, by 40 which a sheet metal structure can be built up of a plurality of separate sheets connected together substantially edge to edge, and to this end the edges of the sheets are so 45 formed that they will engage and interlock at the requisite angles to each other, generally at right angles.

According to this portion of the invention the edges of two plates of metal are 50 formed so that one edge of a first plate composing for instance the back of a case as first herein stated, is bent over at about right angles to its main surface to form a flange, said flange being formed or provided with tongues, or inward projections

such as pins for instance, extending in a plane parallel with the surface of the first plate, slots being formed through the main wall of said first plate; the second plate is formed with projecting tongues on its edge 60 to take into said slots in the main wall of the first plate, such engagement being effected when said two plates are at a proper relative angle. Slots or holes are formed through the wall of the second plate in such 65 positions that when said second plate is brought to the required angle with the first plate, said tongues or inward projections on the edge of the flange of the first plate will enter slots or holes in the wall of the second 70 plate, whereby said plates will be firmly connected together when maintained at a proper relative angle to each other, and can be with equal readiness disconnected when such relative angle is changed. 75

In a preferred construction said first plate is bent over at right angles to its main surface to form a flange at about right angles thereto, and the flange is again bent over to form a channel, and the bent over edge 80 forming the edge of the channel is cut away to produce the tongues which extend in a plane parallel with the surface of said first plate.

In a rectangular structure or casing built 85 according to this invention and adapted to contain say sliding drawers, and where the rearward vertical edges of the side plates are connected by tongues entering slots as above stated, the forward vertical edges of 90 the side plates are bent outwardly and cut away to produce tongues and a front frame is provided having slots in its rearwardly extending flanges into which the tongues on the forward edges of the side plates enter, 95 and the whole structure is maintained rigid and rectangular by bottom or division plates or the like being fitted interiorly of the case. The construction according to this invention thus outlined is obviously applicable 100 to the drawers which are to be contained in such a casing, and to other like structures.

It will be observed that no further fixture 105 of the parts to hold them together is required or called for by this invention, and a rigid structure is produced; that is to say, a tongue on the first part merely enters a slot in the second part and does not extend through and beyond that slot, and a tongue 110

on the second part enters a slot in the first part, and none of the tongues extends through and beyond the slots, as has been proposed in connecting sheet metal structures where tongues on one part have passed through slots in a plate and extended beyond the opposite face of the plate and been retained in such plates by pins passed through the extending tongues.

10 The invention will be further described with reference to the accompanying drawings, whereon Figure 1. is a horizontal section through the tongue and slot connection between two plates according to this invention, Fig. 2. is a side elevation of one of the plates, which we will term the side plate, with the other plate, which we will term the back plate, removed, Fig. 3. is a front elevation of the back plate with the side plate removed, and Fig. 4. is a side elevation of the two plates united as shown at Fig. 1. Figs. 5 to 13 sufficiently show the invention applied to the construction of a casing for containing sliding drawers, Fig. 5. being a 15 sectional front elevation, Fig. 6. a sectional side elevation, and Fig. 7. a rear elevation of the upper part of the casing. Fig. 8. is a perspective view, and Fig. 9. is a vertical section on the line A. A. of Fig. 8. of a 20 front frame. Fig. 10 is a horizontal section of the case, Fig. 11 is a horizontal section through one side of the front frame showing the side plate interlocked therewith, and drawn to a larger scale than Fig. 10, 25 and Fig. 12 is a front elevation of the front vertical edge of the side plate. Fig. 13 shows a portion of the top of the case in section and a means for securing same.

Fig. 14 is a vertical section of one of the 30 drawers for such a case, shown in vertical section, and Fig. 15 is a sectional plan view of the same.

Referring firstly to Figs. 1 to 4 of the 35 accompanying drawings, one vertical edge of a sheet metal plate 1 of a rectangular case is bent over at right angles to its main surface, and the flange 2 is further bent at 3 to form a channel; the rear wall of the 40 channel of the back plate 1 is formed with slots 4 at distances apart, see Fig. 3. and the forward wall of the channel composed of the bent out edge 3 of the metal is cut away at parts so as to produce laterally extending tongues 5, the tongues 5, alternating 45 with the slots 4.

One edge of the side plate 6, Fig. 2. is formed with tongues 7 to enter the slots 4 in the rear wall of the channel of the back plate 1, and near the rear edge of the side 50 plate 6 slots 8 are formed to receive the tongues 5 on the forward wall 3 of the channel of the back plate 1. The tongues 7 of the side plate 6 can then be entered into the slots 4 of the back plate 1 when the 55 plane of the side plate 6 is at an angle

greater than 90° with the plane of the back plate 1, and then as the side plate 6 is brought to a position at right angles to the back plate 1 as shown at Fig. 1. the tongues 5 of the back plate 1 will enter the slots 8 70 in the side plate 6, and thus the vertical edges of the back plate 1 and the side plate 6 will be connected together without the necessity of bending, screwing or bolting either part.

Moreover the tongues on one plate enter the slots in the other plate as described, but do not project through and beyond the slots on the opposite side of the respective plates, or at all events to any appreciable extent, 80 and it is generally not desirable that the tongues should project beyond the surfaces of the plate in which they are entered; in such a connection between two plates according to this invention, one plate, such 85 as 6 Figs. 1 to 4, is bent to form a bead 9 which it has been found improves the appearance of the structure.

The application of the invention to the construction of a sheet metal casing for containing sliding drawers will now be described with reference to Figs. 5 to 13 of the drawings.

The edges of the back plate 1 are connected to the rear edges of the side plate 6 95 by the double interlocking tongues and slots described with reference to Figs. 1 to 4.

The forward edge of each side plate 6, see Figs. 10, 11 and 12, is bent outwardly from the structure at about right angles 100 and cut away at parts to produce tongues 10, Fig. 12, and a front frame 11, see Figs. 8 and 9, is provided of angle section, one flange of the frame 11 extending parallel to the side plate 6, and the said angle flange 105 is slotted at 12 so that by bending the sides 6 toward each other and inserting their edges into the angle frame 11, the tongues 10 on the side plate 6 will enter the slots 12 of the angle frame 11, and thus the structure is connected together composed of a back 1, two sides 6 and a front open frame 11 of angle section.

The front angle frame 11, if the case is to contain drawers or be fitted with shelves, 115 has a suitable number of bars 13 also of angle section, fixed horizontally at proper distances apart and extending between the vertical members of the front frame, each horizontal member 13 having its front flange 120 vertical, flush with the front of the front frame, and its horizontal flange proceeding from the lower edge of the bar, horizontal and inwardly directed.

A suitable bottom plate which it is not 125 necessary to illustrate and which may be formed with downwardly bent edges, is fitted interiorly in the case so that its edges fit against the interior walls and against the front vertical flange of the front frame, 130

and thereby the structure is stiffened; and the tongues 10 on the front edges of the side plates 6 are prevented from leaving the slots 12 of the front frame 11 into which 5 they have been entered.

With such a structure as described horizontal divisions, or as they may be termed shelves (not shown), may be fitted in the structure, said shelves being made of sheet 10 metal with the edges flanged downwardly, the flanges fitting in surface contact with the side plates 6 and the back plate 1 of the structure and with the upstanding flange of the angle bar 13 of the front frame 11. 15 The side and back flanges of each shelf may be formed with downwardly extending tongues which may be received, when the shelf is in position, in slots formed in indented pockets made in the side and back 20 plates 6 and 1, so that the shelves themselves also form structures which serve to augment the rigidity of the case.

The top 14 of the case, Fig. 6, is composed of a metal plate having its edges 25 flanged downwardly; the rear edge of the top 14 at 15 Fig. 6, is connected with the back plate 1 by the double interlocking tongues and slots according to this invention, the top 14 being applied at an angle 30 to the horizontal so as to cause the interconnection of the tongues with the slots as the top 14 is brought to the horizontal position shown where its front edge rests upon the frame 11.

35 This top member is secured in position by a plate 16, the sides of which are flanged downward and outward as at 17 Fig. 13 so as to take under inwardly and upwardly flanged side plates 6, the plates 16 being 40 therefore inserted from the interior of the case. The plate 16 carries lateral bolts 18 which pass through the flange of the plate 16 and through the flanged over tops of the side plates 6.

45 The drawers may be constructed in a manner similar to that described for the case; thus by way of example and as shown at Figs. 14 and 15, the vertical edges of the back plate 19 are united to the rear vertical 50 edges of the side plates 20 by double interlocking tongues and slots as already described, while the forward vertical edges of the side plates 20 are bent outwardly as shown at Fig. 15, so as to enter channels 21 formed in the front plate of the drawer.

The bottom plate of the drawer is similarly connected that is the rear edge of the bottom plate 22 is connected to the lower edge of the back plate 19 at 23 by double 60 interlocking tongues and slots as already described, while forward and lateral downward flanges of the bottom plate 22 enter the lower channel of the front of the drawer, and also enter channels formed in the lower 65 edges of the sides of the drawer, and the

parts are retained in the positions described by a flanged plate 24 fitting into the rear face of the front of the drawer and secured by any convenient means such as by the fixtures of the drawer handle 25. 70

The sides of the case and the sides of the drawers may be fitted with suitable carrying devices to permit the drawers to slide easily into and out of the casing as is already carried out in such structures. 75

Having thus described my invention what I desire to secure by Letters Patent of the United States is as follows:

1. In the construction of metal cases, drawers and the like; connecting the edges 80 of two plates of metal employed in such structures at or about right angles to each other, by bending the edge of the first plate to form a flange at about right angles thereto, forming or providing said flange with 85 tongues or inward projections extending in a plane parallel with the surface of said first plate, and forming slots through the main wall of said first plate, forming the second plate with projecting tongues on its edge to 90 take into said slots in the main wall of the first plate, such engagement being effected when said two plates are at a proper relative angle, and forming slots or holes through the wall of the second plate in such 95 positions that when said second plate is brought to the required angle with said first plate, said tongues or inward projections on the edge of the flange of the first plate will enter the slots or holes in the main wall of 100 the second plate, whereby the said plates will be firmly connected together when maintained at a proper relative angle to each other and can be with equal readiness disconnected when such relative angle is 105 changed.

2. A metal structure, comprising a back plate having its side edges bent upon themselves to form a channel at each side of the plate, said plate being provided in one side 110 wall of said channel with a plurality of slots, the opposite side wall of the channel being cut away to form a plurality of tongues, and side plates each having one edge cut away to form a plurality of tongues adapted to engage the slots at one side of the back plate and having a plurality of slots for engagement with the tongues of said back plate, said back plate being provided with a bead adjacent to the slots thereof. 115

3. A metal structure, comprising a back plate, a pair of side plates each connected to said back plate along one edge thereof, said side plates having a plurality of outwardly extending tongues at the edges opposite said connection, a front structure provided at each side edge thereof with a flange having a plurality of slots adapted to receive the tongues of the side plates, and a plate secured between said flanges for re- 125 130

taining the tongues in the slots.

4. A metal structure, comprising a back plate, side plates and a front structure secured together at their edges to form a rectangular casing, said side plates being provided at their upper edges with inwardly and upwardly extending flanges, a top plate provided with downwardly and outwardly extending flanges adapted to engage the flanges of the side plates, and means for securing the flanges of the side plates and top plate together.
10. A metal structure as set forth in claim

5. A metal structure as set forth in claim

4 and provided with a top member connected at its front and rear edges with the casing 15 and having at its side edges downwardly and inwardly extending flanges adapted to engage the flanges of the side plates.

In testimony whereof I have signed my name to this specification in the presence of 20 two subscribing witnesses.

WALTER CHIPPERFIELD.
